COLUMN FORM CLAMP

Lloyd L. McNair, Cedar Hill, Tex.

Application February 21, 1952, Serial No. 272,739

2 Claims. (Cl. 144—291)

1

This invention relates to concrete forms and it has particular reference to improved equipment for binding concrete forms against expansion under internal pressure imposed by the concrete on the form.

The principal object of the invention is to provide improved means to supplant bulky and unwieldy form binders and to reduce hazards attending the installation of such binders, as well as to reduce the time consumed and the labor expended in such installations. The invention is primarily designed to reinforce the forms for concrete columns and is comprised of four substantially L-shaped corner members adapted for temporary installation on a mounting frame and which serve as bearings for a flexible tensioning or binding element, such as a chain or wire cable the latter functioning to reinforce the walls of the form against outward pressure of the concrete by exerting counter-pressure through bridges situated at opposite extremities of each of the corner members.

Another object of the invention is to provide a concrete form binder in which one of the four corner members is equipped with a stationary and a movable anchorage member for the ends of the flexible binding element, the movable anchorage member being effective to increase and decrease tension in the flexible member through the medium of a threaded bolt actuated by a socket wrench and by virtue of the degree of resiliency of the corner members at their ends nearest to the midsections of the sides of the form. The bridges on the corner members are made to transmit pressure imposed by the flexible member against the walls of the form at the points most vulnerable to outward pressure of concrete within the form.

Broadly, it is the purpose of the invention to reduce the time consumed in applying binders to concrete column forms and to minimize hazards by providing a binder in which the major work in applying the binder may be accomplished by a single worker on deck. Moreover, the improved binder has no protrusions likely to interfere with the movement of workmen or equipment on the deck. The invention further seeks to provide a concrete form binder having all of the prerequisites of conventional binding equipment but has the advantage of being more easily installed on a form, in being lighter without sacrificing strength and less bulky so that it will occupy a comparatively small amount of space during transportation of the equipment from one job to another, thus affording a saving in transportation costs.

2

Other objects will appear as the description proceeds, taken in connection with the accompanying drawings wherein:

Figure 1 is a fragmentary perspective view of a concrete column form on which is shown one of the several binders usually employed on the form and embodying the element of the present invention.

Figure 2 is a view of the form in transverse section.

Figure 3 is a perspective view of the principal corner member carrying the anchoring and tensioning means for the flexible binding element.

Figure 4 is a fragmentary sectional view of a form showing one of the auxiliary corner members.

Figure 5 is a view similar to Figure 4 but showing the principal corner member, and

Figure 6 is a sectional view taken on line 6—6 of Figure 4.

Continuing with a more detailed description of the drawing, reference numeral 10 denotes generally the form structure for a concrete column, the same consisting of vertical planks of shiplap. Arranged in vertically spaced relationship about the form 10 is a series of frames 11 of wood strips. This frame serves as a mounting for the elements of the invention.

The invention consists of three minor corner members such as shown in detail in Figure 4. 30 These corner members are substantially L-shaped so that they will conform to the corners of the mounting frame 11. Each of the three corner members is also substantially L-shaped in transverse section to define a bed plate 12 and a flange 13, the latter terminating short of each end of the bed plate 12 to lend a degree of resiliency to the latter adjacent a bridge 14, which is formed by bending the extremities of the bed plate 12 upon itself to provide a protuberance perpendicular to the side of the mounting frame 11. The purpose of these bridges 14 will be explained presently.

One of the four corner members as shown in detail in Figures 3 and 5 may be referred to as the major corner member. This corner member is identical in construction to the minor corner members and the bed plate 15 of each leg of the major corner member bears against the walls 50 of the mounting frame 11 and upon the flange 16 of one leg of the major corner member is welded or otherwise secured a plate 17 disposed at a slight angle to the longitudinal axis of the bed plate 15 and is apertured at one end to receive a bolt 18. The bolt 18 is threaded onto one end of a substantially rectangular frame 19

and connected to the frame 19 at its opposite end is a swivel 20 having a loop 21 to which is anchored the end 22 of the flexible binding element or wire cable 27. The end of the cable is secured by a clamp 25. The free end of each leg of the major corner member is bent upon itself to form an upstanding bridge 26 onto which the flexible element 27 is elevated to impose tension thereon in a manner similar to the function of the bridges 14 of the minor corner members 10 and on which the flexible member 27 rests when surrounding the column form.

The opposite end of the flexible member or cable 27 is stationarily anchored through the medium of a cleat 28 welded or otherwise stationarily secured to the flange 16 of the companion leg or bed plate 15 of the major corner member. The end 29 of the flexible element 27, after two or three turns about the cleat 28, extends between the stationary and movable jaws 30 and 31 respectively of a clamp 32 and is anchored by a bolt 33 having a head 34. The flexible member then extends around the form under studs 35 on the minor corner members, its opposite end 22 engaging the ring 21 on the adjustable anchoring member or frame 19, as previously explained.

A suitable tool, such as a socket wrench, may be applied to the bolt head 34 to secure the clamp 32 as well as to the head of bolt 18 to effect longitudinal displacement of the frame 19 to tighten the flexible member 27, the flexible member in the meantime having been elevated onto the several bridges 14 and 26 formed on the four corner members, such tension having the effect to exert a force counter to the pressure of the concrete within the form 10, thus to obviate possible distortion of the form.

In installing the form binder on the form 10, the frames 11 are first affixed to the form 10 in vertically spaced relationship. The minor corner members are then applied to the frame 11 by nails to temporarily hold the corner members against displacement in relation to frame 11. The major corner member is then applied to the frame 11 and is held against displacement by driving a nail or pin through the aperture 36 formed in each leg 15 of the member at its approximate midsection. The end of the flexible element 27 is then secured by passing the same around the cleat 28 and in the clamp 32 and the bolt 18 is rotated to draw the frame 19 toward the stationary plate 17 to impose tension on the flexible element 27 which has been elevated onto the several bridges 14 and 26 as previously explained.

One of the objectionable characteristics of other types of form binders is that external pressure on the form is provided by driving wedges between parts of the binder and exterior faces of the form. Hammer blows required to drive the wedges produce vibration within the form, causing the wet concrete to settle and further distort the form. The present invention obviates the necessity for vibrating a form in any manner, thus precluding the settling of the concrete within the form.

It is further evident that without assistance a single workman can readily install all form binders on the column forms with little likelihood of injury to himself since all of the work of tensioning the binder is accomplished through the major corner members and within the confines of the deck on which he is working.

It will be apparent that various changes and modifications can be made in the described and illustrated embodiments of the invention without departing from the invention and it is intended, therefore, in the appended claims to cover all such changes and modifications as fall within the true spirit and scope of the invention.

What is claimed is:

1. In a device for binding a form in the erection of concrete columns, a mounting frame embracing said form, a substantially L-shaped corner member detachably mounted on each corner of said frame whose legs extend toward the mid-section of each side of said frame, a flexible binding member embracing said frame having one end anchored to one leg of one of said corner members and its opposite end adjustably secured to the opposite leg of the same corner member, a transverse bridge formed on the end of each leg of each corner member perpendicular to said frame, said bridges extending outwardly beyond the point of anchorage of said flexible binding member and supporting the same under tension to exert an inward force against each side of said frame.

2. In a device for clamping concrete forms, a frame surrounding said form, a substantially L-shaped corner member detachably secured to each corner of said frame, said corner members each having their legs extending in parallelism with the sides of said frame toward the mid-section thereof, a transverse bridge carried by the end of each leg of each of said corner members and disposed perpendicular to said frame sides, a flexible member embracing said frame, having its ends connected to opposite legs of one of said corner members in closer relation to said frame than the outer ends of said bridges, said flexible member being supported on the bridges of said corner members about said frame and means at one of the connected ends of said flexible member for bringing said flexible member under tension to exert an inward force on said frame through said bridges.
